UNITED STATES PATENT OFFICE.

OSCAR A. SHANN, OF BROOKLYN, NEW YORK, ASSIGNOR TO WESTERN ELECTRIC COMPANY, INCORPORATED, OF NEW YORK, N. Y., A CORPORATION OF NEW YORK.

BELL.

1,387,188.

Specification of Letters Patent. Patented Aug. 9, 1921.

Application filed November 26, 1917. Serial No. 204,026.

To all whom it may concern:

Be it known that I, OSCAR A. SHANN, a citizen of the United States, residing at Brooklyn, in the county of Kings and State 5 of New York, have invented certain new and useful Improvements in Bells, of which the following is a full, clear, concise, and exact description.

This invention relates to improvements in 10 bells, and more particularly to bells which are employed for signaling purposes.

In cases where there are several closely adjacent signal bells, it is frequently desirable to provide bells which produce distinctive 15 sounds so that the source of each signal can be quickly and accurately determined.

Especially in telephone systems where several lines terminate at closely adjacent stations, it is desirable to provide bells having distinctive tones or sounds for such stations 20 so that the subscribers may readily distinguish the calling signals of their respective stations.

The object of the present invention is to 25 provide a simple inexpensive bell which will produce a distinctive, peculiar and pleasing sound.

To obtain this object in accordance with 30 one feature of the invention, a T-shaped slot extending from the edge of the bell toward the crown thereof is provided in the wall of the bell.

These and other features not specifically 35 mentioned above, will more clearly appear from the following specification and the annexed drawing, in which Figure 1 shows a front elevation of an ordinary telephone ringer on which are mounted two bells embodying the invention, while Fig. 2 shows a 40 plan view and Fig. 3, a side elevation of a bell embodying the invention.

In Fig. 1 of the accompanying drawing 1—1 represent two signal bells removably mounted upon posts 7—7 of a telephone 45 ringer of the usual type, comprising a frame

8 which supports the posts 7—7 and the electromagnets 9—9, which magnets actuate the armature 10 to cause the vibration of the clapper or hammer 11. In Figs. 2 and 3, 1 represents a bell provided with a circumferential slot 2 extending substantially parallel to the base or edge of the bell, and with a radial slot 3 extending from the base to slot 2, thus providing free vibratory reed portions 4 and 5 the free ends of which are placed in 55 opposing relation to each other.

It will be readily noted that if the bell is struck by clapper 11 or other medium preferably at a point near the base and away from the slots 2 and 3, the ends 4 and 5 will 60 vibrate somewhat independently of the remainder of the bell wall and as a result, the bell will emit a distinctive sound. By varying the location of the slot 2 relative to the base and thereby changing the length of the 65 slot 3, the pitch of the sound produced may be varied so as to produce numerous peculiar and distinct signals.

What is claimed is:

1. A gong having a circumferential slot 70 and a second slot extending from said circumferential slot to the edge of the gong.

2. A gong having a slot substantially parallel to the edge of the gong and a second slot extending from such first mentioned slot to 75 the edge of the gong.

3. A gong having a T-shaped slot, the base of such slot terminating at the base of the gong.

4. A gong comprising a body portion and a plurality of opposing extensions parallel to the base of the body portion.

5. A gong comprising a body portion and a plurality of opposing extensions thereof of substantially uniform cross-section.

In witness whereof, I hereunto subscribe my name this 21st day of November, A. D. 1917.

OSCAR A. SHANN.
